UNITED STATES PATENT OFFICE.

JAMES H. ELLIS, OF MILWAUKEE, WISCONSIN, ASSIGNOR OF ONE-HALF TO JOHN SCHUSTER, OF MILWAUKEE, WISCONSIN, AND ONE-HALF TO L. E. COLLINS, OF KINGS MILLS, OHIO.

SOUND-BOX.

1,369,795.

Specification of Letters Patent.

Patented Mar. 1, 1921.

Application filed July 25, 1918. Serial No. 246,699.

To all whom it may concern:

Be it known that I, JAMES H. ELLIS, a citizen of the United States, and resident of Milwaukee, in the county of Milwaukee and State of Wisconsin, have invented new and useful Improvements in Sound-Boxes, of which the following is a description, reference being had to the accompanying drawings, which are a part of this specification.

10 This invention has for its object to provide a sound box for sound recording and reproducing instruments, with the diaphragm retaining ring formed in sections and clamping the diaphragm with different pressures at different parts.

Another object of the invention is to provide such a variable pressure sectional clamping ring associated with a diaphragm having its stylus connection out of center and the portion of its edge nearest the stylus connection under greater pressure.

Another object of the invention is to provide a diaphragm with a stylus connection of mica having the needle arm passed therethrough with a rubber insulation therebetween.

With the above and other objects in view the invention consists in the sound box as herein claimed and all equivalents.

30 Referring to the accompanying drawings in which like characters of reference indicate the same parts in different views:

Figure 1 is a plan view of a sound box constructed in accordance with this invention, parts being broken away to show their arrangement;

Fig. 2 is a central sectional view thereof; and

Fig. 3 is a sectional view of the diaphragm.

40 In these drawings 10 indicates the recessed cup member of the sound box which is of suitable material, preferably vulcanized fiber. The diaphragm 11, preferably of vulcanized fiber, is contained in the cavity 45 of this sound box between rubber gaskets 12 and its edges are clamped with pressure between a shoulder 13 of the sound box and a clamping ring 14 which is secured to the sound box by means of screws 15. The 50 clamping ring 14 has an arched guard or bridge 16 extending across it. The ring is cut in two along lines 17 at one side of the bridge so that the sector on which the needle

arm 18 is pivotally mounted is entirely independent from and out of contact with the other sector carrying the bridge.

A stylus connection 20, preferably consisting of a piece of sheet mica, is secured to the diaphragm by having its edge passed through a slit in the diaphragm and cemented thereto on both sides of the diaphragm and it is connected with the needle arm by having the narrow reduced end of the arm passed through an opening therein, a short section of small rubber tube 21 fitting on said end of the needle arm to constitute insulation between the needle arm and the stylus connection.

The flange portion of the clamping ring, which bears on the gasket 12 to clamp the edge of the diaphragm, is deeper on that section of the ring which carries the needle arm and as both sections are clamped by their screws 15 until they tightly bear on the edge of the sound box, the pressure with which the edge of the diaphragm is held by such ring section is greater than the pressure with which the diaphragm is held by the opposite section. As the eccentrically positioned stylus connection is nearer the needle arm, it is the shorter portion of the diaphragm, measured from the stylus connection to the edge, that is clamped with greater pressure by the section of the ring on which the needle arm is mounted.

55 The more tightly clamped portion of the edge of the diaphragm, which is at the same time the portion nearer to the stylus connection, is believed to respond more completely to the high notes, while the other portions of the diaphragm respond more completely to the low notes, so that the same sound box may be used for all records and all parts of the record will receive their proper relative value.

90 The stylus connection of sheet mica serves to give the desired flexibility to permit of the absence of pivotal connections and still faithfully transmit the motions. The rubber tube forms an insulation between the diaphragm connection and the needle arm, while the cement connection of the stylus connection with the diaphragm prevents relative movement between these parts.

95 I desire it to be understood that this invention is not limited to any specific form

or arrangement of parts except in so far as such limitations are specified in the claims.

The use of a rubber tube as insulation between the stylus connection and the needle arm serves the purpose of securely holding the mica against splitting, the ends of the tube flaring while the middle portion is contracted forming in effect a rivet.

What I claim as new and desire to secure by Letters Patent is:

1. In a sound box, a diaphragm-retaining ring formed in sections.
2. In a sound box, a diaphragm-retaining ring formed in sections, one section serving to clamp the diaphragm tighter than the other section.
3. In a sound box, a diaphragm-retaining ring formed in sections and provided with a bearing flange for clamping the diaphragm, the bearing flange on one section of the clamping ring being deeper than the bearing flange on the other to bear with greater pressure on the edge of the diaphragm.
4. In a sound box, a diaphragm-retaining ring having an arched bridge portion extending across it to form a guard for the stylus connection, said ring being split at opposite points at one side of the bridge, and

needle arm pivotally mounted on the section of the ring that is without the bridge. 30

5. In a sound box, the combination, with the diaphragm, of diaphragm-clamping means, said means serving to clamp one section of the diaphragm tighter than the other. 35

6. A sound box comprising a cup-shaped member, a diaphragm fitting therein between gaskets, a retaining ring secured to the face of the cup-shaped member and provided with a flange extending within the cavity of the cup-shaped member and bearing on one of the gaskets for clamping the edge of the diaphragm, said ring being split at opposite points to divide it into sections, the bearing flange on one section being 45 deeper than that on the other, an arch-like bridge connecting the ends of the last mentioned ring section, and a needle arm pivotally mounted on the first mentioned ring section and connected with the diaphragm. 50

In testimony whereof, I affix my signature in presence of two witnesses.

JAMES H. ELLIS.
